BLACKBOARD STAND AND WORK CASE

Filed Feb. 18, 1929

WILLIAM F. SPENCER

By Thomas L. Ryan Attorney

UNITED STATES PATENT OFFICE

WILLIAM F. SPENCER, OF MUNCIE, INDIANA

BLACKBOARD STAND AND WORK CASE

Application filed February 18, 1929. Serial No. 340,774.

This invention relates to improvements in articles of the above mentioned class in which the well known educational scroll is embodied; such articles being intended for and used chiefly in juvenile entertainment, instruction, and educational work in the studio, school room, and home.

Objects of the invention are to provide an article of the kind described, which is economical of manufacture, compact, durable and serviceable; and which comprises in a single unit, a blackboard and stand, and a case for the support of the scroll and the retention of working materials; there being embodied in the case construction, a body plate which constitutes a back or cover plate therefor, and which also constitutes a working surface or table top when the case and blackboard are in the folded or collapsed status.

Further aims of the invention are to provide features of construction whereby the blackboard and case are easily available for use either in combination with each other, or separately, or as a table.

The objects of my invention are accomplished by, and the invention is embodied in the new construction, combination and arrangement of parts described in the following specification, and illustrated in the accompanying drawings.

The several parts of the invention, as they appear in the different views in the drawings, are identified by suitable characters of reference.

Figure 1 is a front view of my improved blackboard stand and work case, the case and the blackboard being in the upright, and inclined positions, respectively, in readiness for use.

Figure 2 is a side view, in the direction indicated by the arrow 2 in Figure 1.

Figure 3 is a top plan view of Figure 1.

Figure 4 is a front view of the upper portion of the case, the mask frame having been removed, and a portion of the case side member being shown in section, disclosing to view, the scroll, and the ends of the rollers thereof.

Figure 5 is an enlarged vertical cross sec-

tion view taken on the line 5—5, and as seen in the direction of arrow 5 in Figure 1.

Figure 6 is a frontal view of the right hand end portion of the case, a portion thereof being shown in cross section taken on the line 6—6 in Figure 2.

Figure 7 is a cross section view taken on the line 7—7, and as seen in the direction indicated by the arrow 7 in Figure 6.

Figure 8 is an enlarged cross section view, showing the positions of the several parts when the case will have been swung down to position in repose on the support frame.

In the blackboard stand and work case shown herein as the preferred form of embodiment of my invention, the support frame is of width and depth to accomodate a blackboard about fourteen by sixteen inches in dimension, and comprises the four wooden uprights 1, 2, 3, and 4. The bottoms of the uprights 1 and 3 are secured to a footed cross bar 5; and the bottoms of the uprights 2 and 4 are secured to a footed cross bar 6. These footed cross bars are similar to each other and their end portions extend to the front and to the rear of the said uprights, the relative distances as shown in Figure 2. The height from the bottom of the footed cross bars to the top of the frame, is about eighteen inches. Upon the upper ends of the said uprights are secured the frame pieces 7, 8, 9 and 10.

A case structure which is adapted to repose on the said support frame, and is connected to one side thereof by hinges 11, consists of body members 12, 13, 14 and 15, secured together at their corners. Upon the inner face and near the frontal edge of each of the members 14 and 15, is a groove 17 of the length as shown in Figure 5. A light wooden rectangular frame 18 whose ends rest movably in the said grooves 17, constitutes a trim or mask in front of the space occupied by the scroll 19. The said scroll comprises a flexible textile sheet bearing the usual miscellaneous sets of lettering, diagrams, images, numerals, and educational illustrations incident to scrolls of its class, and includes the complementary rollers 20 and 21. One end of each of these rollers is plain, and its other end is provided with a central longitudinal

bore 23. Spaced recesses 22 in the case member 15 constitute bearings for the plain ends of the rollers. Spaced holes 24 are provided in the case member 14 in positions aligned with the said recesses 22. To install the scroll, the rollers are disposed with their plain ends in the recesses 22, and the knobbed pintles 24^a, disposed in the holes 24, are inserted into the bores 23 of the rollers, and there secured by a nail or screw 25. By the rotative movement of one or the other of the rollers, the scroll sheet may be moved so as to present to view the different sets of characters thereon.

To yieldably hold the rollers against movement, and also to yieldably hold the mask frame 18 at the position shown, I provide a holder device of the form and construction shown in Figure 7. This holder device consists of a spring wire of predetermined length 20 whose bow shaped body portion 26 is secured to the case member 14 by a staple 27. The one end portion of the wire presses firmly against one of the pintles 24^a, and the opposite portion of the wire is of form to bear 25 against the other of the pintles 24^a, and is brought about in such formation that its curved inturned end 28 bears firmly against the rear face of the end of the mask frame 18. The reason for holding the mask frame 30 yieldably in its position will be presently referred to.

In the lower portion of the case, is disposed longitudinally a light thin plate 30 which is set at an incline, as shown in Figure 5, and 35 at such height that a narrow space 31 between said plate and the adjacent case member, is provided. The compartment thus formed is adapted to retain crayons, chalks, papers, and such other working materials as 40 may be desired. Accumulation of dust particles or sediment is avoided by having the open space 31.

Carried by, and secured to the case members 12, 13, 14 and 15, is a body board or 45 plate 32 which is of the suitable dimensions as shown in the drawings.

A blackboard 33 which is provided with suitably moulded sides 34, has each corner of its frontal portion pivotally connected 50 by pivot pins 35 to the side members 8 and 9 of the support frame. To register on a plane slightly below the plane of the blackboard is a trough piece 36, which is adapted to receive and retain conveniently, the crayons or 55 other working implements which may roll or slide thereto from the surface of the blackboard.

On the inner face of the frontal portion of the members 14 and 15 of the case, are secured the hinge lugs 37. Pivotally connected to each of these hinge lugs is a connector bar 38 which is provided with a longitudinal slot 39. Headed studs 40 and 41, spaced as shown, and secured in the sides of the blackboard, retain these connector bars in slidable

coengagement with the sides of the blackboard. By this construction, combination, and arrangement of parts, the case when in registration with the support frame, as shown in Figure 8, retains the blackboard in 70 position immediately underneath same. The compartment plate 30 being inclined, as shown, prevents all tendency of the contents of the compartment, to become displaced when the case is swung to the lowered position.

By my invention, a minimum amount of material is required, and there is substantial economy in the work and labor involved in the processing of the several parts, and in 80 the assembling of said parts into the finished product. Advantages of having the mask frame retained movably in its position, are that access to the space occupied by the scroll is easily available.

Also there is afforded facility whereby economy may be practiced in the finishing of the interior of the case, either by spraying, or by applying paint or enamel with a brush. This is an item of considerable importance 90 in the manufacture of articles of this class, as hitherto, the finishing of the several interior surfaces; and the installing of the renewals or replacements incident to the use of the scroll, have been relatively inconvenient 95 and costly.

My improved blackboard stand and work case may be supplied to the trade in the completely assembled status, as shown; the case being in repose upon, and the blackboard being retained in horizontal position within the upper portion of the support frame. To use the invention, the case is swung to the upright position; the blackboard being coincidentally brought up to the inclined position as shown in Figure 2 and Figure 5. The connector bars 38 constitute supports for the blackboard, and they also constitute stays whereby both the blackboard and the case are automatically maintained in their respective positions. The tendency of the case to bear rearwardly contributes to the stable support and retention of the blackboard at its raised position, and in which said position it is available to the user for writing or drawing on its surface with crayon or chalk, or for the use thereof as a desk. The compartment provided by the plate 30 is conveniently available for the retention of chalks, crayons, papers and working material; and the scroll is in convenient position for observation, and the knobbed pintles for operating the scroll, are within easy reach.

The weight of the body board 32 imparts such tendency of the case to bear rearwardly, that it is automatically retained stably in the upright position; at the same time it is capable of being easily changed to the horizontal position of repose on the support frame. With the several parts of the invention in 130

the status as shown in Figure 8, the article is useful as a table; the scroll and blackboard, and the contents of the compartment, and also such papers as may be lying on the blackboard, being suitably retained and shielded from misplacement or injury. The body board 32 constitutes a convenient and useful working surface or table top.

Whereas I have shown my invention in the form and proportions, and the details thereof, in the construction deemed preferable, it will be understood that minor changes may be made in the several parts and features of construction, within the scope of the invention as defined by the appended claims, without departing from the spirit of my invention, or sacrificing any of its advantages.

What I claim as my invention, and desire to secure by Letters Patent, is—

1. A blackboard stand and work case, comprising a support frame, a case hingedly connected to one side of said support frame and adapted to rest thereon, a blackboard disposed within said support frame and hingedly connected to the side thereof which is opposite to the hinge connection of the case, and connections between the case and the blackboard, operable when the case is swung to upright position, to raise the blackboard to inclined position, and to retain the case and the blackboard in their said upright and inclined positions, respectively.

2. A blackboard stand and work case, comprising a support frame, a case hinged to one side of said support frame and adapted to rest thereon, a blackboard disposed within the support frame and hinged to the side thereof opposed to the hinge connection of the case, connections between the case and the blackboard operable when the case is swung to upright position, to move the blackboard to and to hold it in inclined position, and to retain the case and blackboard in their respective relative positions, and a body board carried by the case.

3. An article of the kind described, comprising a footed support frame having open top portion, a case hingedly connected at one side of said top portion of the frame and adapted to rest thereon, a blackboard hingedly connected to the top portion of the frame, connections between the case and the blackboard operable when the case is swung to raised position, to move the blackboard to inclined position, and to yieldably maintain the case and the blackboard in their respective positions, and a body board carried by the case.

4. A blackboard stand and work case, comprising a support frame, a case having one side thereof hinged to the frame, a body board carried by the case, a blackboard disposed within the support frame having one side thereof hinged to the frame at position

opposite to the hinge connection of the case, a longitudinally slotted connector bar pivotally connected to opposite sides of the case, and a plurality of headed studs on each side of the blackboard, said studs being engaged 70 slidingly in the slots of said connector bars to maintain said connector bars in parallel alignment with the sides of said blackboard.

5. An article of the kind described, comprising a support frame, a case hingedly connected to one side of said support frame, a scroll mounted in said case, a cover board carried by the case, a compartment in said case having its frontal wall extending from a point adjacent to but slightly spaced from the hinged side of said case and at an inclination toward said cover board, a blackboard disposed within the support frame and hingedly connected to one side thereof, and connections between the case and the blackboard, 80 operable when the case is swung apart from said frame, to move the blackboard to raised position, and to yieldably maintain the case and the blackboard in their relative positions.

6. In an article of the kind described 90 comprising a frame, a case having one side thereof hinged to the frame and a cover board carried by the case, a compartment in said case having its frontal wall extending from a point adjacent to but slightly spaced 95 from the hinged side of said case and at an inclination toward said cover board.

In testimony whereof I affix my signature.

WILLIAM F. SPENCER.
